UNITED STATES PATENT OFFICE.

WILLIAM H. BUTTERWORTH AND JOHN BUTTERWORTH, JR., OF TRENTON,
NEW JERSEY.

THRASHING-MACHINE.

SPECIFICATION forming part of Letters Patent No. 292,731, dated January 29, 1884.

Application filed June 5, 1883. (No model.)

To all whom it may concern:

Be it known that we, WILLIAM H. BUTTERWORTH and JOHN BUTTERWORTH, Jr., citizens of the United States, residing at Trenton, in the county of Mercer and State of New Jersey, have invented certain new and useful Improvements in Thrashing-Machines, of which the following is a specification, reference being had therein to the accompanying drawings, in which—

Figure 1 is an elevation of one side of our improved thrashing-machine, parts of the stacker of which are broken away. Fig. 2 is a section taken vertically and longitudinally 15 through the machine, the stacker proper being detached. Fig. 3 is a top view of the straw-rakes. Fig. 4 is a side view, in detail, of the device for adjusting the toothed concave which is above the thrashing-cylinder. Fig. 5 is a top view of a portion of the concave and its adjusting device. Fig. 6 is a top view, in detail, showing the fan-shaft broken, the eccentrics, the pitman-rods, and one of the lubricating-bearings for said shaft. Fig. 7 20 is a side view of one of the pitman-rods. Fig. 8 is a vertical section of one of the bearings for the fan-shaft. Fig. 9 is a top view of a bearing for the cylinder-shaft. Fig. 10 is a view of the slotted and hinged straw-deflector. Fig. 30 11 is a section of part of one of the rake-heads and its box or cap on top. Fig. 12 is an enlarged view, in detail, of the jointed connection of the folding stacker. Fig. 13 represents a detail sectional view of the removable 35 front of the fan-case.

Our invention relates to that class of thrashing-machines and grain-cleaners combined which are known as "vibrating thrashers," and it consists in certain novel improvements 40 on such machines, which will be fully understood from the following description when taken in connection with the annexed drawings and claims.

Our machine is constructed with the rear 45 end extended beyond the sills, for the purpose of supporting the rear end of the vibrating shaker and the rear part of the straw-rakes. The extension-rails A are arranged in such manner as to set these rails on an inclined 50 plane, which makes a substantial support for the rear portion of the frame, which extends

beyond the rear sills, B, thereby dispensing with legs or props heretofore used. By thus extending the rails or beams beyond the vertical plane of the sills B, we afford a free space 55 for readily removing the chaff, which continually accumulates beneath said extension when the machine is in operation.

B B' are the sills of the machine, which are in the same horizontal plane, but separated 60 by a space which is strengthened and stiffened by a space which is strengthened and stiffened by arched plates B², securely fastened to the outside of the sills, and also to uprights, which constitute a portion of the frame, as shown in Fig. 1. This transverse arch, formed 65 by the divided sills and the stiffening-plates, affords reception for the front wheels in turning the machine short around.

D designates the thrashing-cylinder, which is suitably spiked, and E is the concave, which 70 is shown in Figs. 2 and 5.

F designates the feed-table, which is arranged in front of the cylinder D to receive the grain in the straw preparatory to its being thrashed. This table is constructed with a 75 beveled edge, a, which will deflect or direct the current of air (which accumulates in the semi-cylindrical casing below the cylinder D by the revolutions of said cylinder) through the straw as it is fed between the cylinder and 80 the concave, and thus create a vacuum or sucking in of the dust from the feed-table and from the face of the person who feeds the straw to the machine.

G is the cylinder-casing, inside of which the 85 lower half of the thrashing-cylinder is situated. The rear end of the feed-table F is extended over and within the circumference of the cylinder-casing G, beveling this end a, as described. This beveled end a also serves to 90 deflect the wind produced by the revolution of the cylinder D downward and back into said casing, thus producing eddies therein and keeping the chaff and dust down.

The concave E is pivoted or hinged at its 95 front edge, so that by means of a handle, H, and a cranked pivot, the former having a slotted arc, c, the rear part of this concave can be raised entirely out of the way of the toothed cylinder D when desired. By means of a 100 thumb-screw, c', which is tapped into an offset, c", of the pivotal bearing, the said lever

and concave can be rigidly fixed either in a raised or a depressed position. In front of this concave is a cover, *m*, having a hinged dust-deflector, *n*. *I* designates the upper vibrating shaker, which is in rear of the cylinder *D*, so that the grain in the straw, as it leaves the cylinder and concave after being thrashed, will fall into this shaker. The shaker *I* has two inclined bottoms, the upper one, *e*, being made of perforated sheet metal, and the lower one, *e'*, being an imperforated board. After the straw is thrashed, it is moved over the perforated bottom *e* by a series of rakes, *J*, having curved and straight teeth on their under sides, said rake-bars being hung from cranks *J'*, which give them the proper movement for raking the straw from the thrashing devices and discharging it upon a stacker, hereinafter explained. The cranks *J'* are formed in such manner that the two extreme side bars, *J'*, of the raking apparatus work in unison with each other, while the intermediate rake-bars, *J*, work on different quarters of the stroke. The object of this is to avoid the necessity of slotting the flexible apron or drop-board *K* to allow the rake-bars to reach the point of delivery from the thrashing-cylinder for the purpose of raking away the straw that accumulates on the shaker *I* between said drop-board and cylinder. It will be observed that by our invention of making the two side bars work in unison with each other we are enabled to have them pass along the sides of the drop-board *K* and be connected together by a cross-bar, *L*, between the said drop-board and thrashing-cylinder. This cross-bar is provided on its under side with a row of straight teeth, *a'*, which, when the cranks *J'* are set in motion, rake the straw under the drop-apron *K*, while the other rake-teeth *J*, on the rear side of the drop-apron, reach the straw in their revolutions or stepping motion, and continue to rake the same out of the body of the machine.

45 A thin metallic arm, *a*³, is rigidly secured to each side of the raking apparatus, which arms allow the openings at the ends of the drop-apron to be made quite small. If desired, the rake-bars *J'* may be extended forward to serve as a substitute for the said thin arms. We hang each rake bar or frame on the under side of the cranks, and attach these bars or frames to their cranks by means of caps *a*⁴, so that, in working, the wear of the journals comes on the said caps and not on the rake-bars, thereby greatly increasing the durability of said rake-bars.

The cross-bar *L* is provided with a row of hooks, *a*⁵, which will rake close to the thrashing-cylinder *D* and prevent this cylinder from winding when thrashing wet straw.

Immediately in rear of the thrashing-cylinder is applied a hinged self-adjusting deflector, *M*, which is slotted, as shown in Figs. 2 and 10, to allow the straw-hooks *a*⁵ to pass through it and rake close to the cylinder. This deflector keeps the straw down and aids in pre-

venting it from rising over the raking apparatus.

15 *O* are the side boards on which the top of the machine rests. The upper edges of these boards are inclined forward, corresponding to the inclination of the rake-bars *J*, for the purpose of having the top or cover of the machine an equal distance throughout its entire length above the said rake-bars *J*, thereby preventing the straw from working on top of the rakes on its way from the thrashing-cylinder to the discharge end of the body of the machine.

20 *P* designates the duster, which is located over the thrashing-cylinder and its concave. This duster has a flue through it in the usual manner, the mouth of which is directly over the feed-table *F*, and it extends back of the cylinder *D*. In this duster is a fan, *p*, extending its entire width, the upper part of which revolves in the dust-flue. Just in front of the fan *p* is a board, *p'*, having its upper edge or lip directed toward the fan-wings. By thus constructing and arranging the board *p*, 25 the currents of air will be deflected back, which will tend to produce a vacuum or sucking in of the dust, &c., at the mouth of the flue, which is then caught by the fan-blades and forced out of the rear of the flue. This fan *p* is rotated by means of a cord or belt, 30 passed around a pulley on the thrashing-cylinder shaft, and also around a pulley on the fan-shaft.

25 The thrashing-cylinder *D* is provided with boxes *d*, which are constructed with ears, through which bolts *d* pass, the inner ends of which are rigidly secured to the sides of machine, and their outer ends are provided with nuts, which bear against the ears of the boxes, 35 so that by loosening the screws which pass through slots and hold the boxes down, and turning said nuts, the thrashing-cylinder can be adjusted endwise or held firmly against any side or lateral movement. Thus the teeth of the cylinder will pass between the teeth of the concave centrally and without any lateral play when the cylinder is revolving.

40 The upper vibrating shaker, *I*, contains the perforated sheet-metal riddle or bottom, and also the imperforate bottom, so that the grain and chaff are separated from the straw, and pass through the perforated metal bottom and descend onto the inclined imperforate board bottom *e'* to the lower shaker, *I'*, which contains the sieves for separating the chaff, &c., from the grain. The upper vibrating shaker, *I*, and the lower vibrating shaker, *I'*, have longitudinal vibrating motion in opposite directions communicated to them by means of a double eccentric on the shaft *N* of the fan *V*, acting through the medium of pitman-rods *R*, which are provided with boxes *r r'*, constructed with ears to receive bolts that secure them to said rods. These boxes *r r'* are each less than half of a circle, so that they can be adjusted toward each other, in case of wear, without the necessity of removing them and filing off their edges. The pitman-rods *R* are also provided

with metal straps r^2 r^3 on top and bottom, through slots in which pass metal key-wedges r^6 to take up lost motion caused by wear. These key-wedges are held in position by making the top straps in the form of clamps, which are adjusted by means of bolts r^4 , applied at the backs of the wedges.

At the rear end of the machine, and over the upper vibrating shaker, I, is placed an adjustable hood or cover, S, for the purpose of directing the delivery of the straw to the elevator. This hood is hinged to the top of the back cross-bar of the machine, and is provided at each end with a slotted segment, S', through which a bolt passes that is fast to an upright metal post, S². These bolts are also tapped through small clamps on the inside of the said posts, so that by loosening the bolts the hood S can be adjusted at any desired angle, and then held firmly by screwing up said bolts. Another object of the hood S is to prevent wind-blast from entering the tail of the machine and blowing dust, &c., back and retarding the discharge of the straw. It is important to provide means for adjusting the hood and rigidly securing it at different angles, according to amount of work being done. This we do by the device above described.

T designates the fan-case, in which the fan V revolves for cleaning the grain. This fan-case is constructed with a removable front section, T². The fan is secured to the shaft N, so that by the revolution of this shaft wind is drawn into its case through end openings and forced out of the trunk through the sieve in the lower vibrating shaker, I'. The ends of the fan-shaft N are supported by journal-boxes N', which are rigidly secured to two of the uprights of the main frame, and which inclose longitudinally-split bushings r^7 , which latter can be contracted about the journals of shaft N by means of set-screws r^8 , tapped through the boxes N', and bearing against the bushings near their splits. By this means we are able to compensate for the wear of the journals and bushings, and by means of passages N² we are able to supply oil to the journals and their bushings. The fan-case T is provided at the end openings for the influx of air with adjustable slides T', which are moved by means of a horizontal transverse shaft, W, which is journaled in brackets which are rigidly secured directly to the front removable section, T², of each end of the fan-drum. The removable section of the fan-drum, having connected to it the slides for regulating the draft, as also the looped racks and the shaft, which carries the pinions which work in said racks, it will be readily seen that when said section of the fan-drum is removed the other parts accompany it, and are thus kept together, all being easily separated from the main body of the machine. This shaft W is provided with two pinions, W², which engage with racks W', attached to the said slides T. Hand-wheels are also applied to the ends of the shaft W, so that the operator can turn this shaft from either

side of the machine, and thus by adjusting the said slides together regulate the size of both openings at the ends of the fan-case, and consequently the admission of air therein.

X is the front board or platform, on which the operator stands to feed the machine with grain in the straw. This platform is constructed with a slatted bottom, leaving a space between the slats and the foot-board, and a slat in front thereof, thus forming a pocket, x, adapted to receive extra sieves, &c., that are not in immediate use. The arms of the platform X are connected by links X' to the front sills, B', of the machine, and sustained in a horizontal position by means of chains X² and hooks, which allow the platform to be adjusted in an upright position for compactness.

The fine wire screen I² is used for the purpose of separating cockle and cheat from the wheat after the chaff has been separated therefrom by the blast of the fan V. This screen is constructed with a band, b, or other imperforate smooth surface at its upper part, for the purpose of preventing the cheat or cockle from falling behind the trough G.

Z Z Z is the straw-stacker, which is composed of sections of suitable length jointed together, so that they can be folded in a small space when not in use. The first or lowest section Z is attached rigidly to the frame of the machine, and provided with a hinged door, g, in its bottom, held up by a button, g'. This door may be open or shut during the operation of the machine, for the purpose of delivering the chaff, either separate from or together with the straw, in the stacker.

The usual endless slatted carrier is composed of belts and slats passed around rollers in the usual well-known manner, the lower roller being driven by a belt applied to belt-wheels. (Not shown in the drawings.) The first folding section of the stacker is connected to the rigid section by means of slotted or loose hinges h, which will allow this section, together with its folding fellow, to be adjusted to a higher angle than could be done if the hinges were not slotted, thereby enabling us to build very high and very long stacks. When the said section of the stacker has been adjusted as desired, the joint is made rigid by means of a set-screw, h'.

It will be seen by reference to Fig. 1 that the stacker can be raised or lowered to any desired angle by means of ropes or chains k, connected to the rearmost section of the stacker and to a windlass, L', which is on top of the machine, and which is provided with a ratchet and pawl, as shown in Fig. 1, for holding the stacker at any desired angle.

It will be seen also by reference to Fig. 2 that we apply a hinged guard, g, to the front end of the duster P, which serves as an additional security to prevent dust from flying into the face of the operator while feeding the machine.

Q Q are the inclined spouts, one of which is for discharging the tailings, and the other is designed for discharging the clean grain.

Having thus fully described our invention, what we claim as new, and desire to secure by Letters Patent, is—

1. The combination, with the plate *m*, the 5 casing, the thrashing-cylinder, and the concave, of the beveled dust-deflecting tongue *a* on the feed-table, and the dust-deflector *n*, hinged to the plate in front of the toothed concave *E*, substantially as and for the purposes 10 specified.

2. The combination of the side rake-bars, *J*², the rake-bar *L*, secured to the side rake-heads by narrow strips, the straight and hooked teeth secured to said bar *L*, the thrashing-cylinder, and the hinged slotted deflector *M* at 15 the rear of the thrashing-cylinder, substantially in the manner and for the purposes described.

3. The combination, with the flue-duster *P*, arranged over the concave of the thrashing-cylinder, of the fan, the lipped deflector *p'*, and the hinged dust-deflectors *n' g'*, substantially as described.

4. The combination of the hinged dust-deflector, the lipped deflector, and the fan with the flue-duster *P* and the thrashing mechanism, substantially as described.

5. In a thrashing-machine, the combination, with the shouldered shaft and the thrashing-cylinder, of the journal-boxes therefor, adjustable 30 in a direction with the length of said cylinder,

and the retaining bolts and nuts, whereby the thrashing-cylinder is endwise but not vertically adjustable; substantially as and for the purpose described.

6. The combination, with the front ends of the sills of a thrashing-machine, of a hinged platform, *X*, provided with suspension-chains, and constructed with a pocket, *x*, substantially as and for the purpose described.

7. The combination of the stacker-frame made in sections, the slotted hinge-connections *h*, and the pivot-bolts or set-screws, substantially as described.

8. In combination with the removable section *T*² of the divided fan-drum, the movable slides *T'*, provided with loop-racks *W'*, the hand-wheel shaft *W*, having its journal-bearings attached to said sections *T*² of the fan-drum, and provided with pinions of a diameter to work snugly in said loop-racks, for the purpose of holding the slides parallel with their guides, and moving them in a straight line thereby, substantially as specified.

In testimony whereof we affix our signatures 55 in presence of two witnesses.
